CLAIM

The ornamental design for an air mattress, as shown and described.

DESCRIPTION

FIG. 1 is a perspective view of a air mattress showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Throughout the views, the broken lines represent the portions of the design that form no part of the claim.

1 Claim, 7 Drawing Sheets
